UNITED STATES PATENT OFFICE.

WILLIAM J. COLEBOURN, OF LOUISVILLE, KENTUCKY, ASSIGNOR TO KENTUCKY WAGON MANUFACTURING COMPANY, OF LOUISVILLE, KENTUCKY, A CORPORATION OF KENTUCKY.

DUMPING-WAGON.

1,173,413.

Specification of Letters Patent.

Patented Feb. 29, 1916.

Application filed December 20, 1912. Serial No. 737,795.

To all whom it may concern:

Be it known that I, WILLIAM J. COLEBOURN, a citizen of the United States, residing at Louisville, in the county of Jefferson 5 and State of Kentucky, have invented certain new and useful Improvements in Dumping-Wagons, of which the following is a specification, reference being had thereto in the accompanying drawing.

10 This invention relates to dumping wagons. The best known type of dumping wagons has downwardly swinging bottom doors which are connected by means of chains or other flexible connections with a winding 15 drum by means of which the doors are closed. Suitable devices are provided for rotating the drum in a direction to wind up the connections and close the doors and for releasing the drum to permit the doors to 20 be forced open by the weight of the load which they carry.

The principal object of my invention is to provide a winding drum of this character 25 with a pawl and ratchet actuating mechanism in which the pawl will be automatically moved out of engagement with the ratchet wheel at the end of the winding operation, and will be moved into operative engagement with said wheel when the operator 30 grasps the operating device.

Another object of the invention is to provide a yielding detent pawl to hold the drum against rotation in a reverse direction when the operating pawl has been moved 35 out of engagement therewith, and to provide such detent with a tripping lever which may be locked against movement in a direction to trip the detent.

In the accompanying drawing the figure 40 is a perspective view of the forward end of a dumping wagon showing the application of a door actuating mechanism showing one embodiment of my invention.

In the drawing I have illustrated one embodiment of my invention and have shown the same as applied to one side of the goose-neck 5 of the body 6 of a dumping wagon, which is provided with downwardly swinging bottom doors 7-7, these doors being 45 connected by means of chains 8-8 or other suitable flexible connections with a drum 9.

carried by a shaft 10 that is journaled in a frame 5^a between the sides of the goose-neck 5.

Winding movement is imparted to the 55 drum 9 preferably by an operating lever 11 which is loose on the shaft 10 adjacent one end thereof. Fixed on the shaft 10 adjacent the lever 11 is a ratchet wheel 12 and a pawl 13 is pivoted intermediate its ends to the 60 lever 11 and has its tail portion weighted, as at 14, to cause the nose 15 of said pawl to be normally held out of engagement with said ratchet wheel 12. The pawl 13 is preferably moved into operative engagement 65 with the ratchet by the act of the operator in grasping the hand grip on the operating lever 11. To this end a bell crank handle 16 is fulcrumed at its angle, as at 17, adjacent the hand grip of the operating lever. The 70 lateral arm of the handle 16 and the tail of the pawl 13 are pivotally connected by a rod 18. It will thus be observed that when the operator grasps the operating lever 11 he presses the handle 16 in a direction to 75 toward the lever and as a result the nose 15 of the pawl is engaged with the ratchet 12. It is also to be noted that upon the release of the handle 16 by the operator the weighted end 14 of the pawl will lift the nose 15 80 thereof out of engagement with the ratchet 12 and simultaneously return the handle 16 to its initial position.

Attached to the side of the goose-neck 5 in advance of the ratchet 12 is a plate 19, 85 the rear end of the plate being formed with a laterally extending bearing 20. A suitable detent is provided to prevent the movement of the drum 9 in a reverse direction and, in the present instance, this detent is 90 in the form of a pawl 21 which is disposed within and pivoted intermediate its ends, as at 22, to the bearing 20. The rear end of this pawl is formed with a nose 23 for engagement with the teeth of the ratchet 12 95 and the forward end of said pawl is enlarged, as at 24, to form a weighted end to yieldably hold the nose 23 in engagement with said wheel. When the nose 23 is in engagement with the ratchet wheel, the 100 wheel, because of the tendency of the drum to unwind, causes a direct longitudinal

pressure upon the detent, and as a result, the beveled end of the nose is wedged between adjacent teeth of the ratchet. This wedging action tends to prevent the pawl 5 from being easily disengaged from the ratchet. Therefore in order to overcome this objection, the nose is formed with a break joint as indicated by the numeral 23^a, this joint permitting the pawl to break before becoming disengaged from the ratchet.

In order to trip the pawl 21 to release the drum 9 and the dumping doors 7, a suitable tripping device is provided and is here shown as a foot lever 25 which is pivotally mounted adjacent its rear end upon a bolt 26, carried by a bracket 27 which extends from the plate 19. The rear or short arm of this lever is disposed under the weighted end 24 of the detent 21 and is correspondingly curved to receive said end 24. The opposite or forward end of this lever extends through a suitable guide 28 which is attached to the side of the goose-neck 5 and terminates in advance of said guide in a laterally extending foot piece 29.

A suitable locking device is provided to support the weight of the longer end of the lever 25 and to consequently prevent the accidental displacement of the detent 21. This locking device comprises a latch 30 which is pivotally connected at one end, as at 31, to the side of the goose-neck 5. This latch includes a laterally extending hand piece 32 which is arranged to be disposed under the longer arm of the foot lever 25 and to co-operate therewith to prevent downward movement of the lever.

In passing over rough roads there is a tendency of the detent 21 to become accidentally disengaged from the ratchet wheel 12, and in order to positively lock this detent against such movement, a locking lever 33 is fulcrumed upon the bolt 26, and this lever is formed with a stop shoulder 34, 45 which is adapted, when the lever is moved rearwardly, to engage over the tail 24 of the detent 21. In this position of the locking lever 33, the shoulder also prevents the tripping device from performing its function 50 of releasing the detent 21.

In operation when it is desired to dump the wagon, the stop shoulder 34 of the lever 33 is first disengaged from the tail 24 of the detent 21 by swinging said lever forwardly, 55 and the locking detent 30 is swung upon its pivot 31 from its engagement with the foot lever 25 by the finger piece 32. The operator then depresses the foot lever 25, and as a result, the shorter arm thereof elevates the 60 tail or weighted end 24 of the detent 21, thereby breaking the joint 23^a of said detent and disengaging the nose 23 thereof from the ratchet wheel 12. This permits the drum 9 to readily revolve and consequently 65 unwind the chains 8. When it is desired to

close the doors 7 the detent 30 is returned to its locking position with respect to the foot lever 25. The operating lever 11 is oscillated and, as a result, the nose 15 of the pawl 13 will alternately engage and ride over the teeth of the ratchet wheel 12, thereby rewinding the drum 9. At the same time the nose 23 of the detent 21 will slide over the teeth of the ratchet 12 and will serve to lock said wheel against reverse rotation 75 when the operating lever 11 is swung rearwardly. After the doors 7 have been closed the lever 33 is moved rearwardly and, as a result, the detent 21 will be securely locked in engagement with the ratchet wheel 12.

While I have shown and described one embodiment of my invention it will be understood that this has been chosen for the purposes of illustration only and that I do not desire to be limited to the details of construction shown and described, for obvious modifications will occur to a person skilled in the art.

Having thus fully described my invention, what I claim as new and desire to secure by Letters Patent, is:—

1. In a dumping wagon, a door-operating mechanism comprising a winding drum, a ratchet connected with said drum, an operating lever for rotating the drum in one direction, a detent pivoted intermediate its ends and having its tail weighted to cause the nose to normally engage the ratchet, a tripping lever separate from the detent and adapted to engage said detent to move the latter into an inoperative position, a locking lever for the detent adapted to engage the detent when the tripping lever is in its inoperative position, said locking lever engaging the said detent above said weighted portion and said tripping lever engaging the said detent below the same, and a bracket forming a bearing for said tripping lever and said locking lever.

2. In a dumping wagon, a door operating mechanism comprising a winding drum, a ratchet connected with said drum, an operating lever for rotating said drum in one direction, a detent pivoted between its ends and having its tail weighted to cause its nose to normally engage said ratchet, a tripping lever separate from the detent and adapted to engage the weighted end thereof to move the detent out of engagement with said ratchet, means to retain said tripping lever in its inoperative position, and a locking lever for the detent adapted to engage the detent when the tripping lever is in its inoperative position.

3. In a dumping wagon, a door operating mechanism comprising a winding drum, a ratchet connected with said drum, an operating lever for rotating the drum in one direction, a detent pivoted intermediate its ends and having its tail weighted to cause

the nose to normally engage the ratchet, a tripping lever separate from the detent and adapted to engage said detent to move the latter into an inoperative position, a locking lever for the detent adapted to engage the same when the tripping lever is in its inoperative position, a plate rigidly secured to said wagon and having a bracket forming a bearing for said detent and also having a

5

second bracket forming a bearing for said tripping lever and said locking lever.

In testimony whereof I affix my signature in presence of two witnesses.

WILLIAM J. COLEBOURN.
